(57) CLAIM

The ornamental design for a combined toilet brush and holder, as shown and described.

DESCRIPTION

FIG. 1 is a perspective view of a combined toilet brush and holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom side perspective view thereof;

FIG. 9 is a perspective view thereof, shown in a state of use; and,

FIG. 10 is an enlarged detail view of area 10 shown in FIG. 9.

Any shading and cross-hatching are not features of the design but are utilized to illustrate the surface contours of the combined toilet brush and holder design in the drawings. The broken lines in the drawings depict portions of the combined toilet brush and holder that form no part of the claimed design. The encircling broken lines in FIGS. 9 and 10 depict the unclaimed boundary of the enlarged detail views.
